United States Patent Office.

NICHOLAS S. VEDDER, OF TROY, NEW YORK, ASSIGNOR TO EDWARD J. HICKS AND GURDON G. WOLFE, OF SAME PLACE.

Design No. 2,989, dated March 31, 1868.

DESIGN FOR THE DOOR AND LEG OF A COOK'S STOVE.

The Schedule referred to in these Letters Patent and making part of the same.

TO ALL WHOM IT MAY CONCERN:

Be it known that I, NICHOLAS S. VEDDER, of the city of Troy, in the county of Rensselaer, and State of New York, have invented or produced a new and original Design for Plates of a Cooking-Stove, of which the following is a full and exact description, reference being had to the accompanying photographs, in which—

Figure 1 is a door, and

Figure 2 a leg of a stove, having my said design.

My new design for the door consists of a surface, composed of alternate upright ribs *a*, grooves *b*, and flat strips *c*, crossed by imitation strap-hinges *d d*, with rivet-heads *e*, and surrounded by a strap-like moulding, *f*, all shaped and arranged together as shown in fig. 1; and the design for the leg consists of the central grooved surface *g*, crossed horizontally by the ornamental strap *h*, with an ornamental base, *i*, and side ornaments *j j*, all shaped and arranged together as represented in fig. 2.

What I claim as my invention or production, and desire to secure by Letters Patent, is—

The design for the door and leg of a stove, herein set forth and shown.

In testimony whereof, I have hereunto set my hand, this 14th day of February, 1868.

Witnesses:

L. STONE,

AUSTIN F. PARK.
